(57) **CLAIM**

The ornamental design for a USB aromatherapy diffuser, as shown and described.

DESCRIPTION

FIG. 1 is a front perspective view of a USB aromatherapy diffuser showing my new design;

FIG. 2 is a rear top perspective side view thereof;

FIG. 3 is a rear view thereof;

FIG. 4 is a front view thereof;

FIG. 5 is a right side view thereof;

FIG. 6 is a left side view thereof;

FIG. 7 is a top view thereof;

FIG. 8 is a bottom view thereof;

FIG. 9 is a top front perspective view thereof;

FIG. 10 is a bottom perspective view thereof; and,

FIG. 11 is a bottom rear perspective view thereof.

The broken lines in the drawings illustrate portions of the USB aromatherapy diffuser that form no part of the claimed design.
